UNITED STATES PATENT OFFICE.

WILLIAM H. BRADFIELD, OF POMEROY, OHIO.

TOY.

995,053.

Specification of Letters Patent. Patented June 13, 1911.

Application filed February 14, 1911. Serial No. 608,502.

To all whom it may concern:

Be it known that I, WILLIAM H. BRADFIELD, a citizen of the United States, residing at Pomeroy, in the county of Meigs and

5 State of Ohio, have invented certain new and useful Improvements in Toys, of which the following is a specification, reference being had to the accompanying drawings.

10 My invention relates to improvements in toys and particularly to improvements in darts and slings for shooting them, and consists in the construction, combination and arrangement of devices hereinafter described and claimed.

15 In the accompanying drawings—Figure 1 is a side elevation of my improved sling and dart showing the same connected together for use in shooting the dart. Fig. 2 is a detail perspective view of the sling. Fig. 3 is 20 a similar view of the dart.

The dart 1 in accordance with my invention has the head 2 and the shaft 3. The head is provided at its front end with a point 4, and is provided on one side with 25 a radially projecting stud 5. The rear end of the shaft is split and is provided with a vane or feather 6, to direct the dart in a straight line.

30 The sling comprises the handle 7, elastic 8, and a link 9. The handle is made of a single piece of wire and is provided at its upper end with an eye 10. The lower end of the handle is doubled and bent to form a hand hold 11, the terminal of the wire forming the handle being twisted, together with that part of the handle immediately above the hand hold, as at 12, thus strengthening the construction of the handle. The elastic 8 is preferably, and is here shown as a rubber band or ring which is engaged with the eye 10. The elastic band or ring is also engaged by an eye 13 at the front end of the link 9. The said link is also provided at its rear end with an eye 14 for engagement 45 with the stud 5, of the head of the dart so as

to connect the dart to the link and hence to the sling and enable the dart to be drawn back from the handle so as to stretch the elastic.

When the dart is released the elastic 50 shoots the dart and as the dart passes over the handle the link 9 becomes detached from the stud 5. The eyes 13, 14 at the front and rear end of the link 9 are off-set from the intermediate portion 15 of the link so that 55 they will lie closely against the side of the head of the dart provided with the stud 5, to facilitate the engagement of the eye 14 with the said stud. As soon as the eye 14 has thus been engaged with the stud, the link 60 is kept with the eye in engagement with the stud by the tension of the elastic.

It will be understood that any suitable spring may in practice be substituted for the elastic herein specifically described, within 65 the scope of my invention, and it will also be understood that changes may be made in the form, proportion and construction of the various parts within the scope of the appended claim. 70

I claim:

In combination with a dart having a head provided with a stud projecting from one side thereof, a sling comprising a handle, an elastic connected to the handle and a link 75 connected to the elastic, the link being provided at its ends with eyes off-set therefrom, and lying in a common plane, one of the eyes being connected to the elastic, the other being adapted for engagement with the stud 80 of the dart, so that when the dart is connected to the sling the eyes of the link bear on one side of the head of the dart.

In testimony whereof I hereunto affix my signature in the presence of two witnesses. 85

WILLIAM H. BRADFIELD.

Witnesses:

CHARLES WOLF,
SCOTT McQUIGG.
